UNITED STATES PATENT OFFICE.

EDWARD L. WHITE, OF BROOKLYN, NEW YORK.

INSTEP-ARCH SUPPORTER.

1,279,193.

Specification of Letters Patent. Patented Sept. 17, 1918.

Application filed May 21, 1918. Serial No. 235,817.

To all whom it may concern:

Be it known that I, EDWARD L. WHITE, a citizen of the United States, and resident of the borough of Brooklyn, in the city and State of New York, have invented a new and useful Improvement in Instep-Arch Supporters, of which the following is a specification.

The object of my invention is to provide certain improvements in the construction, shape and arrangement of the several parts of the arch supporter whereby the arch supporter may be readily adjusted to suit different requirements in the treatment of the instep.

An important feature of my invention is the decreasing and increasing of the play of the arched supporting plate members against the tension of one or more coil springs disposed lengthwise of the supporter and spanning the arch.

Another important feature is the shape of the arched supporting plate so that when weight is applied to the arch support, there will be a tendency for the outer side of the support to be depressed and the inner side raised to cause the plate to give greater support to the inner side of the arch of the foot where the support is needed.

My invention generally comprises an arch support having two or more members, means flexibly connecting them, tension springs and means for adjusting the limit of the arching movement of the members.

My invention more particularly comprises in its preferred form, an arched supporting plate divided transversely into front, intermediate and rear members, means flexibly connecting the members, spring means normally holding the members at the limit of their arching movement and adjusting means to limit the arching movement.

Practical embodiments of my invention are represented in the accompanying drawings in which,

Figure 1 represents one embodiment in top plan,

Fig. 2 represents the same in bottom plan,

Fig. 3 represents the same in side elevation enlarged in its normal arched position, and

Fig. 4 represents the same in side elevation in its flattened position against tension of springs.

Fig. 5 represents in bottom plan another embodiment,

Fig. 6 is a view of the same in top plan.

Fig. 7 represents the same in side elevation enlarged with the adjustable means for limiting the arching movement in one position, 60

Fig. 8 is a similar view with the adjustable means in another position.

In the embodiment shown in Figs. 1 to 4 inclusive, the arched supporting plate is divided transversely into front and rear 65 members 1 and 2 and an intermediate member 21. This plate has a short outer side 3 and a long inner side 4 connected by curved ends 5 and 6. This plate is arched longitudinally and this, together with the shape of 70 the plate, creates a tendency when weight is applied thereto, to depress the outer side of the plate and raise the inner side so as to cause the plate to give greater support to the inner side of the arch of the foot, where the 75 support is most needed.

Means such as one or more flat spring metal strips 7, (in the present instance two) 80 flexibly connect the members, bridging the dividing lines 22, 23, between the members and riveted or otherwise secured at 9 to said members.

Spring means such as one or more lengthwise disposed coil springs 10, in the present instance two, are provided for normally holding the members at the limit of their arching movement, said springs bridging the dividing lines 22, 23, and riveted or otherwise secured at 11, at their ends to the front and rear members 1 and 2. Adjusting 90 means for limiting the arching movement of the members comprises two depending screws 12 having their heads countersunk in the members 1 and 2, and a bridge piece 13 spanning the dividing lines 22, 23 and bearing 95 against the under faces of the members 1 and 2. Nuts 14 threaded on the ends of the screws 12 bear against the bridge piece 13.

In the embodiment shown in Figs. 5 to 8 inclusive the arched supporting plate is divided transversely into front and rear members 1 and 2 only. The means which flexibly connects these two members in this form is shown as comprising the two flat spring metal strips 7 bridging the dividing line 8. 105 The two coil springs 10 also bridge the dividing line 8. The adjusting means for limiting the arching movement of the members comprises a depending screw 12 having its head countersunk in the members 1 and 2 at 110 the dividing line 8, a rigid bridge piece 13 which spans the said dividing line and a nut,

14 threaded on the screw and bearing against the bridge piece 13.

In both of the embodiments above described, the limit of the arching movement 5 of the plate is increased or diminished to increase or flatten the arch to the desired extent by screwing or unscrewing the nuts 14. The greater the limit of the arching movement the greater will be the play of the 10 members under the tension of the coil springs 10.

A suitable protective covering 20 may be provided for the arched plate in both of the 15 embodiments, which covering may be cut away to gain access to the kerfs in the heads of the screws 12.

It is obvious that various changes may be resorted to in the construction, shape and arrangement of the several parts without 20 departing from the spirit and scope of my invention; and hence I do not wish to limit myself to the embodiments herein shown and described, but

What I claim is:

25 1. In an article of the character described, an arched plate divided transversely into a plurality of members, means flexibly connecting the members and one or more lengthwise disposed coil springs for normally holding the members at the limit of their arching movement.

2. In an article of the character described, an arched plate divided transversely into a plurality of members, means flexibly connecting the members, one or more lengthwise disposed coil springs for normally holding the members at the limit of their arching movement and adjusting means to limit the arching movement.

40 3. In an article of the character described, an arched plate divided transversely into a plurality of members, means flexibly connecting the members, one or more lengthwise disposed coil springs for normally holding the members at the limit of their arching movement and adjusting means to limit the arching movement, said last named means comprising a bridge piece, a depending screw and an adjusting nut engaging 45 said screw and bridge piece.

4. In an article of the character described, an arched plate divided transversely into a plurality of members, means flexibly connecting the members, one or more lengthwise disposed coil springs for normally holding 55 the members at the limit of their arching movement and adjusting means to limit the arching movement, said last named means

comprising a bridge piece, depending screws and nuts engaging said screws and bridge 60 piece.

5. In an article of the character described, an arched plate divided transversely into a plurality of members, means flexibly connecting the members, adjustable means for 65 decreasing and increasing the play of the members and spring means for normally holding the members at the limit of their arching movement.

6. In an article of the character described, 70 an arched plate divided transversely into a plurality of members, means flexibly connecting the members, adjustable means for decreasing and increasing the play of the 75 members and spring means for normally holding the members at the limit of their arching movement, said means comprising depending screws, a bridge piece carried thereby and nuts engaging said screws and bridge piece.

80 7. In an article of the character described, an arched plate divided transversely into a plurality of members, means flexibly connecting the members, adjustable means for decreasing and increasing the play of the 85 members and spring means normally holding the members at the limit of their arching movement.

8. In an article of the character described, 90 an arched plate divided transversely into a plurality of members, one or more flat spring metal strips flexibly connecting the members, adjustable means for decreasing and increasing the play of the members, and one or more coil springs connecting the front 95 and rear members for normally holding the members at the limit of their arching movement.

9. In an article of the character described, 100 an arched supporting plate divided transversely into a plurality of members and means flexibly connecting the members, said plate having a short outer side and a long inner side connected by curved ends.

10. In an article of the character described, 105 an arched supporting plate divided transversely into a plurality of members, means flexibly connecting the members, said plate having a short outer side and a long inner side connected by curved ends, and 110 spring means normally holding the plate at the limit of its arching movement.

In testimony that I claim the foregoing as my invention, I have signed my name this 20th day of April, 1918.

EDWARD L. WHITE.
